UNITED STATES PATENT OFFICE.

CHARLES DAVIS, OF PARIS, FRANCE.

FACE-POWDER BOX.

1,203,501.

Specification of Letters Patent. Patented Oct. 31, 1916.

Application filed January 29, 1915. Serial No. 5,073.

To all whom it may concern:

Be it known that I, CHARLES DAVIS, subject of the King of Great Britain, residing at Paris, France, have invented certain new and useful Improvements in Face-Powder Boxes, of which the following is a specification.

This invention relates to improvements in receptacles of the type in which a sieve is adapted to rest on the surface of the contents to prevent excessive removal thereof by a pad or brush which is applied to remove some of the contents, the sieve being pressed down by the brush or the like and descending with the contents as they are consumed.

The object of the invention is to provide an improved receptacle of this type which will be especially suitable for containing fine powders, such as face powder, and with which a fine puff, such as a swan's down puff, can be used effectively and without liability of spilling or scattering of the powder.

An important feature of the invention comprises a sieve of textile fabric such as silk or cotton gauze which is stretched initially over the surface of the powder and is adapted under the light pressure or action of the light puff to follow or descend with the gradually falling upper surface of the powder.

The invention also comprises the combination of details hereinafter specified and claimed.

In the drawings, Figure 1 is a sectional elevation of one form of powder box according to the invention. Figs. 2 and 3 are sectional elevations of another form, the sieve being shown at different levels.

In the form of the invention illustrated by Fig. 1, the box comprises a cylindrical body 1, and a bottom 4 having a vertical cylindrical portion 5. A cover 6 fits as usual outside the body 1 and onto the top edge of the portion 5. A flexible sieve 3 of fabric such as silk gauze is secured at its circumference to a ring 8 about which it is lapped and then secured to a carrier by which it can be raised and lowered. For example, the ring 8 is glued to the ledge 7' of a frame 7 adapted to slide inside the body 1. The frame 7 has means, such as tabs 9 of silk ribbon, by which it can be raised. The sieve 3 is caused to follow the lowering level of the powder 3' owing to the pressure of the puff when in use.

In the form illustrated by Figs. 2 and 3 the tabs of silk ribbon are secured to a stationary but preferably removable frame 10, the upper ledge or overhanging rim 12 of which is slotted as at 13 to permit of the passage of the tabs 9. One end of each tab is secured to the underside of the rim 13 and the other is turned in under and glued to the ring 8. The tabs thus form loops. A lining 14 is provided within the box extending part of the depth of the same, the frame 10 resting on the upper edge of said lining.

It will be noticed that in both of the forms illustrated, the fabric sieve 3 is secured at its circumference to a frame which has a sliding fit within the box so that the only means of exit for the powder is through the sieve and spilling or scattering of the contents when the box is opened brusquely is avoided, and only the requisite small quantity can be removed by the puff at any time.

I claim:

1. A box for containing powder having a frame which has a sliding fit within said box, an inwardly projecting ledge on the frame, a sieve of textile fabric secured to said ledge, said ledge and sieve being arranged on the lower side of said sliding frame and means for raising said frame, said raising means being attached to and extending above said frame.

2. A powder box having a lining within the box and extending part of the depth of the same, a frame slideable in said lining and conforming closely to the sides thereof, an inwardly projecting ledge on said frame, a sieve of textile fabric secured to said ledge, said ledge and sieve being arranged on the lower side of said frame, a second frame arranged above the lining and fitting the interior of the box at the top thereof and resting on the upper edge of said lining, an inwardly projecting rim on said second frame, and means passing from said inwardly projecting rim on the second frame to the slideable frame to raise the same, substantially as described.

In testimony whereof I have signed my name to this specification in the presence of two subscribing witnesses.

CHARLES DAVIS.
